CLAIM

The ornamental design for an electrical connector, as shown and described.

DESCRIPTION

FIG. 1 is a front elevation view of an electrical connector, showing the new design;

FIG. 2 is a top plan view thereof;

FIG. 3 is a rear elevation view thereof;

FIG. 4 is a right side elevation view thereof;

FIG. 5 is a left side elevation view thereof;

FIG. 6 is a bottom plan view thereof;

FIG. 7 is a front, top and right side perspective view thereof;

FIG. 8 is a rear, bottom and right side perspective view thereof; and,

FIG. 9 is a front, bottom and right side perspective view thereof.

The broken lines shown in the drawings illustrate portions of the electrical connector that form no part of the claimed design.

1 Claim, 4 Drawing Sheets
